UNITED STATES PATENT OFFICE.

LAVALETTE L. LOGAN, OF JOHNSTOWN, PENNSYLVANIA.

FLUID-OPERATED ACTUATING DEVICE.

No. 834,825.

specification of Letters Patent.

Patented Oct. 30, 1906.

Application filed July 27, 1905. Serial No. 271,511.

To all whom it may concern:

Be it known that I, LAVALETTE L. LOGAN, a citizen of the United States, residing at Johnstown, in the county of Cambria and 5 State of Pennsylvania, have invented new and useful Improvements in a Fluid-Operated Actuating Device, of which the following is a specification.

This invention relates to a fluid-operated actuating device capable of various uses. I 10 have found it of particular advantage in connection with a mine-door. In this particular use the object of the device is to open the mine-door against a given pressure with as little water as possible. The mine-door is 15 hard to start to open; but after it has been partially opened the pressure against it is very much lessened. By virtue of my fluid-operated actuating device I am enabled to 20 apply to the door initially sufficient power to readily start it open, the power thereafter expended in fully opening the door being relatively low. I am enabled to accomplish the 25 results in question with a minimum amount of water, thereby securing economy. I have set forth one advantageous use to which the device may be put. There are others, as will be understood from my opening statement, I have also indicated that economy of water 30 is assured. It will be understood that this is the case when water is employed as the fluid agent for effecting the operation of the device. Where other fluid, such as air or steam, is employed, equal economy follows their use. 35 In the drawings accompanying and forming a part of this specification I illustrate a simple form of embodiment of the invention, which, to enable those skilled in the art to make and use the same, I will set forth in detail in the following description, while the 40 novelty of the invention will be included in the claims succeeding said description.

In said drawings, Figure 1 is a plan view, and Fig. 2 a longitudinal sectional elevation, 45 of a fluid-operated actuating device involving my invention.

Like characters refer to like parts throughout the views.

The device is shown as including in its 50 make-up a base-plate, as 2, illustrated as fastened to the foundation-piece 3, which may be a plank, bolts being provided for the purpose. From one end of the foundation-plate is shown as rising a circular flange 4, which, 55 as will hereinafter appear, constitutes a stop for limiting the motion of a plunger or piston,

as 5. This plunger or piston 5 is represented as mounted for reciprocation in a barrel or cylinder, as 6. I use the several terms hereinbefore mentioned in their broad senses, 60 and the same applies to those hereinafter used. For example, while I term the part 6 a "barrel" or "cylinder," it is evident that the same need not be circular in cross-section. One end, or what is shown as the left end in 65 Fig. 2 of the barrel or cylinder 6, is fitted into an annular flange extending laterally from the marginal portion of the flange 4, a screw-thread union between the two constituting a simple means of detachably uniting them. 70 The flange 4 really presents a head for one end of the barrel or cylinder 6, the opposite end of the latter being represented as closed by a head or cap 7, which can be detachably fitted in place by a screw-thread joint, as indicated in Fig. 1. The piston 5 is shown as being at the limit of its backward stroke in Fig. 2, and it advances until it strikes the flange or stop 4. The stroke of the piston 5, 75 which latter might be considered a main piston, is reduced with respect to a second or auxiliary piston hereinafter described. Their effective areas are also different, the effective area of the main piston being greater than that of the auxiliary one. 80

The barrel or cylinder 6 might be considered as a main one, an auxiliary barrel of less diameter than the main one being shown at 8. The two barrels in the present instance are concentric. The barrel 8 extends through a 90 central perforation in the flange 4 and also through a registering perforation in the flange 9, located at the end of the plate 2 opposite that provided with the flange 4. The walls of the two perforations guide the auxiliary 95 barrel 8 in its longitudinal reciprocative movements. The inner end of the auxiliary barrel is shown as extended through and in screw-threaded engagement with the main piston 5. I have shown as threaded onto the 100 extreme inner end of the auxiliary barrel 8 a cap or nut 10, a packing-ring and a washer being interposed between the piston and cap. By tightening up the cap or nut 10 the packing and washer can be tightly jammed between the same and the piston, so as to provided for an absolutely water-tight fit of the piston 5 in its barrel 6. The cap 10 therefore 105 closes the open end of the cylinder 8 and really presents a head therefor, and it is perforated for the entrance of an operating fluid into the auxiliary barrel. 110

The piston shown within the auxiliary barrel is designated by 12, and to it is represented as swiveled one end of the rod 13. The piston 12 is packed substantially like the 5 piston 5 and for the same purpose.

To supply an agent to the two cylinders for operating the same, I have represented a pipe, as 14, tapped into the head or cap 7. The fluid therefore can enter the cylinder 6 to operate its piston 5, the latter as it advances advancing the barrel 8. Subsequently the piston 12 will be operated so as to move it longitudinally of its cylinder or until it strikes the marginal flange of the ring, as 15, threaded onto the outer end of the barrel 8, which ring constitutes a stop for limiting the advancing stroke of the piston 12. It will be apparent, of course, that the stroke of the piston 12 is greater than that of the piston 5.

20 I may employ the device in connection with a mine-door such as that disclosed in my contemporaneously-pending application for patent, filed December 15, 1904, Serial No. 237,043. In the mine-door of the application there is connected operatively thereto a piston-rod, and in practice I would connect a rod, such as 13, to such a door.

It is believed the operation of the apparatus will be understood from what is hereinbefore stated. Upon the admission of water into the cylinder 6 the piston 5 is first operated to apply to the door a relatively powerful force to start it open. When the piston 5 has done its work, it will strike the stop 4, the 35 door at this time having been opened sufficiently to relieve it from air-pressure. The door, however, is not wide open. As the piston 5 moves it carries therewith the cylinder 8. After the initial opening movement 40 of the door the piston 12 becomes effective for opening the door to the necessary extent, such piston being driven forward and away from the cap or head 10 by water entering its cylinder 8 by way of the perforations in the 45 head or cap 10.

What I claim is—

1. The combination of a main cylinder, a piston in the said cylinder, an auxiliary cylinder extending entirely through the said piston and through one head of the main cylinder, the other head of said main cylinder having a supply-port, a cap fitted to the inner end of the auxiliary cylinder, constituting a head therefor and having a supply-port for 55 said auxiliary cylinder, and a piston in the auxiliary cylinder.

2. The combination of a main cylinder, a piston in the said cylinder, an auxiliary cylinder extending entirely through the piston and 60 through one head of the main cylinder, the other head of said main cylinder having a sup-

ply-port, a cap threaded onto the inner end of the auxiliary cylinder, a packing between said piston and the cap, held in place by the latter and adapted to traverse the inner surface of the main cylinder, and a piston in the auxiliary cylinder, said cap having a port to permit a fluid to be supplied to the auxiliary cylinder.

3. The combination of a main cylinder, a piston in said cylinder, an auxiliary cylinder extending entirely through the piston and through one head of the main cylinder, the other head of said main cylinder having a supply-port, a cap threaded onto the inner end of the auxiliary cylinder, a packing between said piston and the cap, held in place by the latter and adapted to traverse the inner surface of the main cylinder, a piston in the auxiliary cylinder, said cap having a port to 70 permit a fluid to be supplied to the auxiliary cylinder, a rod jointed to the last-mentioned piston, and a flange having a perforation through which the auxiliary cylinder passes.

4. The combination of a main cylinder, a piston in said cylinder, an auxiliary cylinder extending entirely through the piston and through one head of the main cylinder, the other head of said main cylinder being detachably mounted and having a supply-port, 75 a cap threaded onto the inner end of the auxiliary cylinder, a packing between said piston and said cap, held in place by said cap, surrounding one end of the auxiliary cylinder and adapted to traverse the inner surface of 80 the main cylinder, and a piston in the auxiliary cylinder, the cap having a port to permit a fluid to be supplied to the auxiliary cylinder, a rod jointed to the last-mentioned piston, and a flange having a perforation through which the auxiliary cylinder passes.

5. The combination of a main cylinder, a piston in said cylinder, an auxiliary cylinder extending entirely through the piston and through one head of the main cylinder, the other head of said main cylinder being detachably mounted and having a supply-port, 85 a cap threaded onto the inner end of the auxiliary cylinder, a packing between said piston and said cap, held in place by said cap, surrounding one end of the auxiliary cylinder and adapted to traverse the inner surface of 90 the main cylinder, and a piston in the auxiliary cylinder, the cap having a port to permit a fluid to be supplied to the auxiliary cylinder, a rod jointed to the last-mentioned piston, and a flange having a perforation through which the auxiliary cylinder passes.

In testimony whereof I have hereunto set my hand in presence of two subscribing witnesses.

LAVALETTE L. LOGAN.
